UNITED STATES PATENT OFFICE

2,651,512

GAS AND LIQUID CONTACT APPARATUS

Jules Pierre Voleau, Boulogne-sur-Seine, France,
 assignor to L'Air Liquide, Societe Anonyme
 Pour l'Etude et l'Exploitation des Procedes
 Georges Claude, Paris, France

Application July 19, 1949, Serial No. 105,532
 In France August 4, 1948

1 Claim. (Cl. 261—114)

1

This invention relates to gas and liquid contact columns and deals with improvements in devices for distributing the liquid from one plate to the next lower one, in the columns, for instance in distilling and rectifying columns.

An object of this invention is to facilitate the circulation of the liquid and of the froth on the plates, and their flowing down through the downspouts.

Another object is to reduce the portion of plate area occupied by the downspouts.

A further object is to provide for the arranging of the plates as close as possible above each other.

Still another object is to lessen the losses of pressure head due to the changes in direction of the liquid through the hydraulic seals and the distributing pipes.

A still further object is to insure that the distributing pipes are full with the liquid containing no or only a few gas bubbles, and so to take up relatively narrow diameters for these pipes.

Other objects of the invention will appear during the course of the following specification, referring to the accompanying drawings.

Those objects are attained, according to the present invention, chiefly by arranging the liquid distributing tubes under the plate that they feed, that is to say in the space between this plate and the next lower one.

In the drawings:

Fig. 1 is a diagrammatic view of a portion of a column constructed according to the prior art;

Fig. 2 is a diagrammatic view of a portion of a column having plates and downspouts constructed according to one form of the present invention in which the flow of liquid over the plates is centripetal;

Fig. 3 is a similar view illustrating a form of the present invention in which the flow of liquid over the plates is centrifugal;

Fig. 4 is a fragmentary perspective view, partly in section, of an apparatus according to the present invention in which the flow of liquid over the plates is centrifugal;

Fig. 5 is a view similar to that of Fig. 4 showing a modified form of construction.

On Fig. 1 is shown in vertical section a part of a conventional column, provided with superimposed plates S, S₁, S₂ and intended to be of the centripetal circulation type. Over plate S taken as an example, radial tubes T are fitted on box G and the open ends of these tubes are above the peripheral part of the plate. In the central part of the plate is a funnel-like downspout D, the

2

low part of which projects into a box G₁, provided with radial tubes T₁ that are like the tubes T and situated at a higher level than the low edge of downspout D so that the whole makes a hydraulic seal.

The operation of such device is as follows:

The liquid, discharged from the next upper plate, not shown, is conducted according to the arrows through box G, then by means of the pipes

10 T outwardly towards the external part of plate S. It flows along this plate from the periphery towards the centre, contacting meanwhile with the gas flowing up through the perforations of the plate and bubbling through the liquid. When 15 reaching the central region of the plate, the liquid is discharged into the downspout D, the box G₁, then into the tubes T₁ and flows similarly on the plate S₁.

The inconveniences of this standard arrangement, which become especially striking with large-sized plates, are as follows:

1. The discharge tubes interfere with the circulation of the froth that may occur on the plate and in the case of plates on which it is desired 25 to impart to the liquid an oblique movement so as to increase its period of contact on the surface of the plate and the tubes prevent any tangential component in the movement of the liquid.

2. The liquid flows into downspout D₁ along the 30 circumference of this downspout, but its flow is hindered at this spot by the distribution tubes T₁ and to obviate this drawback, a relatively large diameter should be given to the end part of D₁, thus exaggerating its dimension in relation to 35 the diameter of the plate. These two drawbacks are of special importance when it is desired to arrange the plates as close as possible above each other.

3. The changes in direction of the liquid in 40 passing through the hydraulic seal set up a loss of pressure head that acts as a check on the flow of the liquid.

4. The distribution tubes T₁, T₂ are not filled with liquid but enclose in their upper portion gas 45 bubbles arising from the atmosphere of the plate, which bubbles oppose the satisfactory flowing of the liquid and necessitate large diameters for these distributing tubes.

As shown in Fig. 2, the bottoms of successive 50 plates are denoted by S', S'₁, S'₂, and it will be seen that underneath each bottom of the plates pass distributing pipes T₁, T'₁, T'₂ respectively feeding the plates S', S'₁, S'₂. In Figure 2, one end of the tubes T' emerges into the central downspout D' connected to the bottom of the plate S',

the other end of the tubes T' emerges in the annular guttering G' of which the upper part is flush with the bottom of the plate. Under these conditions, the liquid going down, for instance, from the plate S' through D'1, is fed on to the lower plate S'2 through the pipes T'2; the liquid having circulated over S'2 flows through D'2, of necessity as represented, while going over the top of a weir. It is a fact that it meets the tubes T'2, but it has already at this spot acquired a certain speed and its discharge is fixed only by the circumference of D'2.

The hydraulic seal is formed by the assembly of the central container D'1, the tubes T'2 and the annular guttering G'2; the tubes T'2 are filled continually, therefore, with liquid.

According to Figure 3, the tubes T'1 placed under the plate S'1, emerge at one of their ends into an axial container G'1, their other horizontal end is connected to vertical tubes D'1, emerging on the upper plate S'. Under these conditions, the liquid overflowing from the plate S' into the downspouts E' and the descending pipes D'1 fills the pipes T'1 then the central container G'1 so as to emerge then on the plate S'1 from which it flows through the downspouts E'1 and the pipes D'2.

The hydraulic seal is formed by the assembly of the tubes D'1 and T'1 and the containers G'1.

The periphery of the plate (Fig. 4) may be taken up wholly by the downspouts alternating with the tubes coming down from the upper plate. It is thus simple to give both of them a large enough cross section. For structural convenience, the peripheral portion of the plate (Fig. 5) may be formed also by a rim R' carrying openings for the downspouts E'1 and bored for the passing of the pipes D' descending from the upper plate. The main thing is that there should be no direct communication between the free spaces above and below a given plate, which is effected, as an example, by the two arrangements of Figures 4 and 5.

Generally speaking, the figures show plainly that the flow of the liquid is much simpler than in the previous cases.

From the structural point of view, use may be made to advantage of the tubes T'1 as supports for the surface S'1.

Use may be made likewise of the tubes for fastening below the latter a wire gauze or any other arrangement for checking the liquid globules resulting from a possible priming on the lower plate.

What I claim is:

A gas and liquid contact apparatus comprising a column, a plurality of superposed contacting plates mounted in said column, liquid discharge means on each plate having an inlet portion positioned above the plate to maintain a layer of liquid on the plate, the liquid discharge means having a bottom portion below the bottom of the next lower plate, conduit means extending beneath said next lower plate for conducting liquid from the lower portion of said discharge means up to said next lower plate, said conduit means cooperating with said discharge means and with the upper portion of the discharge means of the next lower plate to form a liquid trap to provide a liquid seal of a depth equal to the distance between the lowermost portion of the top wall of said conduit means and the inlet portion of the discharge means of said next lower plate and included within the distance between the inlet portion of the discharge means of said next lower plate and the liquid level in the lower portion of said last mentioned discharge means.

JULES PIERRE VOLEAU.
